UNITED STATES PATENT OFFICE.

ROBERT McC. JOHNSTONE, OF ROSELLE PARK, NEW JERSEY, ASSIGNOR TO CAMERON
MACHINE COMPANY, OF BROOKLYN, NEW YORK, A CORPORATION OF NEW YORK.

SAFETY DEVICE.

Application filed October 1, 1927. Serial No. 223,315.

This invention relates generally to safety devices and has more particularly reference to safety devices to be employed in connection with winding machines.

- 5 The main object and feature of the invention is to provide means whereby the rotation of the machine will of itself automatically throw the safety device into protective position.
- 10 In the accompanying drawings the invention is shown in a concrete and preferred form in which

Fig. 1 is a view in section, largely diagrammatic, of parts of a winding machine embodying one form of the invention.

15 Fig. 2 is a detail view with parts broken away and in section looking in the direction of arrow 2 of Fig. 1.

Fig. 3 is a view similar to Fig. 1 with the 20 parts of the safety device occupying a non-protective position.

Fig. 4 is a detail sectional view substantially on the plane of line 4-4 of Fig. 3.

Fig. 5 is a view similar to Fig. 1, but showing a modified form of the invention.

Fig. 6 is a detail view of some of the parts of Fig. 5 and showing the guard in protective position.

Fig. 7 is a sectional view substantially on 30 the plane of line 7-7 of Fig. 6.

Fig. 8 is a horizontal sectional view substantially on the plane of line 8-8 of Fig. 7.

The machine selected for illustration and to which the invention may be applied is, 35 in the present instance, a winding machine provided with front and rear winding drums A and B and with a winding shaft C on which material D is accumulated by frictional engagement with the drums. Owing 40 to the fact that the rotation of the parts is in the direction indicated a grave danger exists that the operator of the machine may be caught in the nip between the drum and the wound material. To obviate this dan-

45 ger a guard member 1 is provided to shield the nip between the drum and wound material, and, in the present instance, this guard member is mounted on two arms 2 that are pivoted at point 3. A suitable motor element is provided whereby said guard member will automatically move into protective position, and a simple motor element for this purpose would be a means for normally urging the guard into protective posi-

tion. Such means may take many forms 55 but are here shown as a counterweight 4. There are times when the operator must have access to the nip, as when cleaning the machine, and a suitable latch 5 is therefore provided by means of which the guard member 60 may be held in non-protective position. The specific means here used are as follows: latch 5 is provided with two arms that are pivoted at 6 on arms 2 of the guard member, and said latch is biased to fall when the 65 guard member is depressed as shown in Fig. 3 and to insure that it will always fall to the left in the illustration a keeper 10 is provided against which pin 9 will be stopped if the latch should attempt to cross over its 70 dead center. The latch is preferably provided with material 12 similar to that used for brake linings.

It will now be seen that when the guard is depressed into the non-protective position 75 shown in Fig. 3 latch 5 will bear against a movable part of the machinery, here the hub or shaft of one of the rotatable drums. So long as the drum remains at rest the guard will be held by the latch, but when the 80 drums begin rotation the latch will be automatically released and weight 4 will move the guard into protective position.

A suitable stop pin 11 on the guard member may be used to limit the downward 85 movement of the latch, and a stop pin 13 in the framework of the machine may be used to limit the upward movement of the guard member.

In Figs. 5 to 7 is shown a modified form 90 of the invention in which the guard takes the form of a reciprocatory member consisting here of a wire screen 20 supported by two vertically extending T-bars 21 that slidably engage a plurality of sets of rotatable 95 guide rollers 22. The motor element that moves the guard into protective position consists here of counterweights 26 carried by flexible connections 24 that pass over sheaves or pulleys 25, said connections being secured to the lower end of the guard member. It will be seen from the above construction that counterweights 26 normally tend to urge the guard member upwardly or 100 into protective position to shield the nip between the front winding drum and the accumulated material on the winding shaft, the extent of this movement being limited 105

by a suitable stop as 27 which comes against one of the guide rolls 22. The latching means are, in this instance, constructed as follows: 28 indicates two arms or bell cranks pivotally supported at 28^a on the framework, said arms being provided at one end with a pivotally supported latch 29. At the other end of arms 28 is pivotally carried a counterweight 29^a that tends to move arms 28 down to the right (Fig. 5) so as to permit latch 29 to turn on its pivot and engage the hub of A when the guard has been depressed. So long as the machine is at rest the parts will remain in this position, but, when drum A begins to rotate, latch 29 will be released and the guard member will rise into protective position. One advantage of this construction is that if the hand of the operator should be adjacent the nip, it will be thrown upward and outward by the rising guard member or gate.

I claim:

1. The combination with a winding machine having a surface winding drum and a winding shaft to receive wound material that engages the surface of the winding drum, a pivotally supported guard member to protect the nip between the drum and wound material, means to urge the guard member, in a given direction on its pivot, into protective position, and a latch to engage a movable part of the winding machine to hold the guard member in non-protective position so long as the movable part

is at rest but automatically released upon movement of said movable part.

2. The combination with a winding machine having a surface winding drum and a winding shaft to receive wound material that engages the surface of the winding drum, a pivotally supported guard member, to protect the nip between the drum and wound material, a latch to engage a movable part of the winding machine to hold the guard member in non-protective position so long as the movable part is at rest but automatically released upon movement of said movable part, and means to automatically move the guard member into protective position upon release of the latch.

3. The combination with a winding machine having a surface winding drum and a winding shaft to receive wound material that engages the surface of the winding drum, a guard member to protect the nip between the drum and wound material, means to urge the guard member into protective position, and a pivotally supported latch to engage a rotatable part of the winding machine to hold the guard member in non-protective position so long as the rotatable part is at rest but automatically released upon rotation of said rotatable part.

Signed at Brooklyn in the county of Kings, city of New York, and State of New York, this 27 day of Sept. 1927.

ROBERT McC. JOHNSTONE.
